Primary Examiner — Leanne Was-Englehart*Assistant Examiner* — Molly Loch(74) *Attorney, Agent, or Firm* — Condo Roccia Koptiw LLP(57) **CLAIM**

The ornamental design for a speed bump connector as shown and described.

DESCRIPTION

FIG. 1 is a top front perspective view of a speed bump connector according to the present invention;

FIG. 2 is a bottom rear perspective view of FIG. 1;

FIG. 3 is a front view of FIG. 1;

FIG. 4 is a rear view of FIG. 1;

FIG. 5 is a top rear perspective view of FIG. 1;

FIG. 6 is a top view of FIG. 1;

FIG. 7 is a side view of FIG. 1;

FIG. 8 is a bottom front perspective view of FIG. 1;

FIG. 9 is bottom view of FIG. 1; and,

FIG. 10 is a side view of FIG. 1.

The broken lines in the drawings illustrate portions of the speed bump connector that form no part of the claimed design.
